UNITED STATES PATENT OFFICE.

THOMAS BILYEU, OF PORTLAND, OREGON, ASSIGNOR, BY MESNE ASSIGNMENTS, TO INTERNATIONAL MONEY MACHINE COMPANY, OF TERRE HAUTE, INDIANA, A CORPORATION OF INDIANA.

PAPER-CURRENCY-PAYING MACHINE.

1,178,378.

Specification of Letters Patent.

Patented Apr. 4, 1916.

Application filed May 13, 1913. Serial No. 767,335.

To all whom it may concern:

Be it known that I, THOMAS BILYEU, a citizen of the United States, residing at Portland, in the county of Multnomah and 5 State of Oregon, have invented certain new and useful Improvements in Paper-Currency-Paying Machines, of which the following is a specification.

The present invention appertains to machines for handling money, and particularly those of the type adapted to select and deliver, under manual control, a predetermined sum of money comprising either coinage or paper currency, or both.

15 Machines of a construction to which this invention especially relates are illustrated in the pending application of William S. Overlin, filed November 5, 1912, Serial Number 729,704, and a pending application of myself filed January 18, 1913, Serial Number 742,958. In the first mentioned application, the paper currency handling instrumentalities are utilized primarily for the purpose of effecting a separation of a bill or 20 note from a pile, and delivery of the same from the machine. In the second mentioned application, in addition to other improvements, the pneumatically controlled devices for insuring proper separation of a piece of 25 paper currency from a pile and delivering the same, are furthermore utilized to control in a peculiar manner certain operation of the machine effected by the removal of a bill manually from the deliverer.

30 In the machine which is hereinafter set forth, I have made a further advance in construction and operation in the way of simplifying the mechanisms generally, but of greater importance, I dispense with the 35 need of two separate manual operations of the machine to effect selection and delivery of the paper currency. The operations of selecting and delivering a piece of paper currency, separately performed heretofore, are combined in this machine.

A problem with which I have been confronted in the development of money handling machines involving the use of paper currency delivery mechanism, has been to 40 provide for the delivery of currency in large sums, which sums necessitate the delivery of two or more bills of the same denomination. Little difficulty would be experienced in accomplishing this by the mere provision

of more than one bill holder for currency 55 of each denomination. However, a desideratum in this art is the production of a machine of minimum size, so the indefinite duplication of the denominational bill holders is impracticable in meeting the requirements of a commercial machine. For this reason I have devised novel means whereby manipulative devices are adapted to control by one operation thereof, one or more delivery movements of the deliverer of a predetermined bill holder. Under these conditions, by pressing a predetermined key, for instance, a single bill of the denomination of \$10.00 may be delivered or ejected from the machine, while, in order to obtain 60 \$30.00, a separate key may be operated one time only, and through the provision of the necessary instrumentalities, the deliverer will perform automatically three delivery movements, each time carrying to the delivery point a bill. By reason of the foregoing, it will be obvious that I only require a sufficient number of units in a paper currency delivering machine, to correspond 65 with the number of denominations of bills 70 or notes handled, in order to deliver money in sums ranging from the minimum capacity of the machine to its maximum.

The manner in which the objects hereinbefore referred to have been attained, as 75 well as other general and detail features of the present machine, will be understood upon reference to the description found hereinafter, and to the accompanying drawings, in which—

Figure 1 is a side elevation of a machine embodying the invention, the casing of the machine being broken away to bring out more clearly the several mechanisms, and the deliverer illustrated in projected position as when delivering a bill. Fig. 2 is a rear view, the suction head being in normal position, and dotted lines showing how it may be moved upward to admit a fresh pile of bills to the holder. Fig. 3 is a top plan 90 view, certain parts such as the platform or body of the bill holder being broken away to afford an uninterrupted view of the cylinder and adjacent parts, and other parts shown in section, and the suction head in 95 abnormal position. Fig. 4 is a detail view showing the particular mechanism of the keyboard, or manipulative controlling

means, and Fig. 5 is a plan view of the same, the key stems shown in section. Fig. 6 is a sectional view on the line 6—6 of Fig. 3, dotted lines illustrating the holder elevated as when supplying a bill to the deliverer. Fig. 7 is a front view, with the casing omitted or broken away.

Briefly speaking, the present money handling machine embodies one or more holders for bills or paper currency, each holder adapted to support a pile of bills practically in the condition in which it is received from a bank or counting house. Associated with the holder is a deliverer comprising a suction head adapted upon relative movement of the holder and deliverer, to separate a bill from the pile on the holder. The deliverer is also adapted to carry the bill to a suitable delivery point. The relative movement of the deliverer and bill holder to effect preliminary separation of a bill from the pile is pneumatically controlled, being caused primarily automatically by the mere removal of the bill from the deliverer when the bill reaches the delivery point. The delivery movement of the deliverer, however, is controlled by manipulative members, such as keys, and the details of the parts just referred to will now be set forth.

The base of the machine is designated A in the drawings and since a commercial machine embodying the invention, would comprise only a plurality of delivery units, I have illustrated and will now describe one only of these units.

A suitable bill holder 1 in the form of a table or platform is vertically movable above the base A, said holder having spaced downwardly extending guide members 2 intermediate its ends, the latter having projections or bearings 3 which operate in spaced guides 4 that project upwardly from the base A. The holder 1 is supported by a piston rod 5, the upper end of which is secured to the under side of the holder and the lower end of which is bifurcated to receive a link 6. The lower end of the link is pivotally connected to the rod 5 adjacent to a piston 7 which carries said rod and the upper end of the link is pivotally connected with an arm 8 extending from a rock shaft 9. A coiled spring 10 is secured at one end to the post 11 and at its other end is attached to another arm 12 which projects downwardly from the shaft 9 aforesaid. The spring 10 normally tends to raise the holder to the uppermost limit of its movement, which movement is afforded for the purpose of permitting the holder 1 to carry the pile of bills thereon upward to the deliverer 13 arranged above the same. It may be noted here, however, that the normal position of the holder 1 is at the lower limit of its movement, said holder being thus held against the tension of the spring 10 by

means of suction in the cylinder 14 in which the piston 7 operates. Said cylinder 14 is connected by a pipe 15 with a pipe 16 transverse thereto, the pipe 16 being in turn connected with a vertical pipe 17 that extends upwardly from and is in communication with a main suction conduit 18. Suction created in the conduit 18 is also created in the cylinder 14 by reason of communication established through the pipes 15, 16 and 17. Said suction is furthermore regulated by means of valves 19 and 20, the valve 19 controlling the communication between the pipes 16 and 17, whereas the valve 20 controls communication between the pipes 15 and 16. By the provision of the valves 19 and 20, the amount of suction in the pipe 15 and that in the pipe 17 may be nicely regulated, this being advantageous because the pipe 17 has a tubular extension 17^a with which a pipe 21 that forms a part of the deliverer, is telescopically connected. The pipe 21 has a goose neck 22 provided with a suction head 23 arranged above the holder 1. Said suction head has apertures in its bottom portion, the latter being adapted to engage with a paper bill or note uppermost on the pile carried by the holder 1. The telescopic connection between the parts 17^a and 21 is shown at 17^b and permits of longitudinal sliding movement of the member 21 with the head 23, such movement being required in effecting delivery of a bill to the delivery point. Projecting upwardly from the holder 1 are a plurality of guides or retaining fingers 1^a which maintain the bills on the holder in place during the movement of the latter. If desirable, the downwardly projecting guide finger 24 may be carried by the part 17^a and also co-operates to prevent displacement of the bills on the holder 1.

The goose neck 22 which has the suction head 23, is movably mounted on the pipe 21, there being an interlocking lug and slot connection 25 intermediate said parts. Normally the lug is interlocked with the slot of the pipe 21, but by pulling outwardly on the goose neck, said lug may be disengaged from the slot and will then permit the head 23 to be raised into a vertical position, as shown in Fig. 2 in dotted lines and in full lines in Fig. 3. With the head 23 upraised, it is very easy to replenish the supply of bills on the holder 1, and a spring is utilized to resiliently hold the parts 21 and 22 interlocked by the connection 25 aforesaid.

Near the front of the machine is a rock shaft 26 which carries a lever 27 near one end and a stop arm 28 near its other end. A spring 29 is connected at one end with a projection 30 on the arm 28, the other end of said spring being anchored to the base at 31. Said spring normally tends to pull the stop arm 28 rearwardly together with the lever 130

27, the latter being connected by a link 32 with the deliverer. Movement imparted to the lever 27 therefore will be likewise imparted to the pipe 21 of the deliverer and the goose neck 22 and head 23 which are carried by said pipe. Near its lower end, the lever 27 has a pin 33 which passes through a slot 34 at one end of an operating bar 35. The operating bar 35 has a slot 36 intermediate its ends through which a guide and pivot pin 37 passes. Also at its rear end the bar 35 has a slot 38 receiving a pivot pin connection 39 between said bar and a vertically movable lock member 40. The upper end portion of the lock member 40 is formed with a hook catch 41 and an arm 42, and said member 40 is connected by a slotted link 43 with the lever 27. On its rear extremity the operating bar 35 has a lateral projection 44, which projection is engageable by a pawl 45, the rearmost end of which is pivotally connected with the arm 12 of the shaft 9. A spring 46 is secured at one end to the projection 44 of the bar 35 and the other end of the spring is secured to the short arm of a somewhat L-shaped plate 47. The plate 47 is adapted for slight tilting movement, its front end having, as a support, the pin or bearing 37 and the rear end being connected with the bar 35 and lock member 40 by the pivot connection 39.

It will be observed that the nose of the pawl 45 is adapted to engage with the projection 44 of the operating bar 35, said engagement taking place during downward movement of the arm 8 and rearward movement of the arm 12. By such engagement between the parts 35 and 45, the member 45 is adapted to draw the operating bar 35 rearwardly and downwardly, thereby placing the spring 46 under considerable tension and causing the notch at the front end of the slot 34 to be engaged with the pin 33 of the lever 27.

On the shaft 9 is also carried a restraining arm 48 having at its front end a lock pin 49 and on downward movement of the arms 8 and 48, caused by suction in the cylinder 14, the lock pin 49 engages with the arm 42 of the lock member 40 and depresses the lock member sufficiently to impart a slight oscillatory movement to the operating bar 35, disengaging the projection 44 from the pawl 45. In other words, the bar 35 is released from the pawl 45 after said pawl has moved the bar 35 rearwardly. It is at this time that the notch of the slot 34 engages the pin 33, and were it not for the fact that other restraining means is employed to prevent forward movement of the bar 35 to actuate the lever 27 and deliverer, said member 35 would immediately move forward after the part 45 is disengaged from the projection 44. The last mentioned restraining means which cooperates with the bar 35 and lever 27 to

prevent delivery movement of the deliverer will now be described. It may be noted, however, that just above the pawl 45 is located a stop 50 that limits the upward play of the pawl during operation of the machine. 70

As shown most clearly in Figs. 2, 3 and 4, manipulative means is employed to control the bill discharging or delivering movement of the deliverer, and said means preferably comprises a plurality of keys *a*, *b* and *c*. The keys *a*, *b* and *c* are depressible by the application of finger pressure and are supported in an auxiliary casing *B* suitably carried by the base *A*. Mention has heretofore been made of the provision on the rock shaft 26, near the front of the machine, of the stop arm 28. The said arm 28 has an outwardly projecting stop pin 28^a at its upper end and adapted for coöperation with a pivoted stop lever 51 supported, at 52 on the casing of the machine. The lever 51 has a catch 53 that normally rests in a position to engage the stop 28^a of the arm 28. When the lever 51 is in the position shown in Fig. 4, namely, in the path of movement of the stop 28^a, it is obvious that the shaft 26 and deliverer actuating lever 27 cannot move forwardly under the action of the spring 46 co-operating with the operating bar 35. The catch 53 must be removed from the path of the stop 28^a in order that the delivery movement of the deliverer may be effected. It is for this purpose that the manipulative keys *a*, *b* and *c* are utilized, the key *a* having a projection *a'* on its stem arranged to engage the outer extremity of an extension 51^a of the stop lever 51. At one side of the lever 51 is a pivoted plate 54 having a projection 55 extending therefrom beneath and in contact with the stop lever 51. The plate 54 is composed of spaced elements or plate members and its axis is common with that of the lever 51. At its free end, the plate 54 carries a detent 56, the upper end of which has a series of steps or notches adapted to be engaged with a detent flange 57. A spring 58 tends to cause engagement of the parts 56 and 57. A second spring 59 is so connected with the plate 54 that it tends to raise said plate with the detent 56. If desired, a flat spring 60 may be utilized to supplement the spring 59, said spring 60 bearing upwardly against the under side of the plate 54. Suitable springs 61 tend to hold the keys *a*, *b* and *c* upraised. The operation of the manipulative controlling means just referred to will be set forth in the general description of the operation of the machine. 100

General operation of the machine: Assuming that the bill holder 1 is supplied with a pile of bills or paper notes of a certain denomination and that the parts are in the positions substantially as shown in Fig. 2, as soon as the pneumatic means by 125 130

which a suction is created in the conduit 18, begins to operate, said suction immediately tends to pull downwardly the piston 7 in the cylinder 14. This lowers the holder 1 and by reason of the suction through the pipes 17, 17^a and 21, and the head 23, the uppermost bill of the pile on the holder is separated from the pile and retained in engagement with the under side of the head 23, 5 ready to be delivered (see Fig 6). During the downward movement of the piston 7, the arm 8 of the shaft 9 is forced downward, thereby placing the large spring 10 under tension that will later cause the holder to 10 be elevated to supply another bill to the deliverer. As the arm 8 tilts downwardly, the restraining arm 48 is tilted in the same direction and the arm 12 is moved rearwardly with its pawl 45 engaged with the 15 projection 44 of the operating bar 35. The pawl pulls the operating bar rearwardly increasing the tension of the actuating spring 46 of said bar, and on the final downward movement of the piston, the pin 49 of the 20 restraining arm 48 strikes the lock member 40 and oscillates the operating bar 35 so as to disengage its projection 44 from the pawl 45, and simultaneously the notch of the slot 34 is engaged with the pin 33 of the lever 25 27. The lever 27 being on the shaft 26 having the stop arm 28, is prevented from causing delivery movement of the suction head 23 under the influence of the spring 46, owing to the fact that the pin 28^a of the 30 stop arm 28 is engaged by the catch 53 of the stop lever 51. Supposing, now, that the key *a* is depressed, its projection *a'* will engage the portion 51^a of the lever 51, depressing said lever. Since the lever 51 engages the pin 55 of the plate 54, the plate 54 is depressed simultaneously with the lever 51 and carries downwardly the notched 35 40 45 50 55 60 65 70 75 80 85 90 95 100 105 110 parts 51 and 54 sufficiently to depress the detent 56 the distance of two notches. Under these conditions, the release of the stop 28^a effected by depression of the key *b* causes 5 said stop to move forward into engagement with the detent 56 and simultaneous forward movement of the deliverer. However, when the stop 28^a engages the detent 56, the third notch of the detent is disengaged from the 10 projection 57 and the second notch is engaged with said projection and though catch 53 moves upward slightly part 56 still holds the catch down clear of the stop 28^a. Since the second notch of the detent engages the 15 projection 57, the catch 53 of the lever 51 is yet retained by the detent 56 out of the path of movement of the stop 28^a as just mentioned and therefore, on removal of the bill from the delivery head 23, said head will 20 return to its normal position to automatically receive another bill and then move outwardly to deliver the second bill, owing to the fact that the catch 53 is retained out of the path of the stop 28. On the second 25 movement outward of the head 23 carrying the second bill to the delivery point, the stop 28^a strikes the detent 56 the second time in this particular operation of the machine so that the first notch at the bottom of the detent engages the projection 57, releasing and 30 permitting sufficient upward movement of the catch 53 of the lever 51 to engage said catch again with the stop 28^a and thus prevent another delivery movement of the delivery head. 35

It should be borne in mind that when the detent 56 is depressed by any one of the keys *a*, *b* or *c* the spring 58 pulls the detent to the right as shown in Fig. 4 so as to bring 40 a side of the notched portion above that engaged by the member 57, into a position in which it will be struck by the stop 28^a in the movement of the latter. The movement of the stop 28^a is always for a constant distance, namely sufficient merely to trip the detent 56 enough that it may be normalized by a single or step by step movement dependent upon which of the keys is operative. 45

The principle of operation as above set 50 forth, is practically the same in respect to the key *a* excepting that depression of the latter key through its projection *c* lowers the members 51 and 54, and consequently the detent 56, until the fourth notch of said detent is engaged beneath the projection 57 and it takes three successive operations of the deliverer, all performed automatically, as soon as the bill is removed from the head, in order to restore the detent 56 to its normal position, whereupon the catch 53 will 55 be released to coact with the stop 28^a to prevent any further movement of said deliverer until one of the keys is again depressed.

With the manipulative controlling means 60 just described, it is obvious that by depress-

ing one of the keys mentioned, a single bill will be delivered; another key will control the delivery of two bills, and still another key will control the delivery of three bills. By adding notches to the detent 56, any suitable number of successive operations of the deliverer may be effected by the mere depression of a single key and the removal of the bill from the delivery head as soon as the latter assumes its delivery position. In 70 this connection, it must be borne in mind that the detachment of the delivered bill from the suction head 23 controls subsequent automatic operation of the holder 1 and head to separate another bill from the pile 80 in the holder and deliver said bill if the catch 53 is so adjusted that the deliverer is free to move forward.

In Fig. 3, a conventional form of suction creating device, such as an exhaust fan 85 or equivalent means, is illustrated at C, the same being connected with the conduit 18 by a flexible hose 18^a. Where the machine of this invention is used in department stores, or establishments employing a pneumatic cash system, it will be obvious that said machine could readily be connected with a suction conduit of such system in a very advantageous manner.

In regard to the operation of the several 95 mechanisms that have been fully described above, it should be noted that the suction means in operating upon the piston 7, constitutes the means acting through the pawl 45, to store up power in the spring 46 and 100 by which power the operating bar 35 is driven when the stop 28^a is released by the keys. Necessarily, the suction created in the cylinder 14 must be sufficient to overcome the tension of the main spring 10 that 105 acts to cause relative movement of the holder and deliverer when the former supplies a bill to the latter. Again, it should be noted that after the deliverer is actuated by the spring 46, operating the bar 35, said 110 spring is not under tension momentarily so that it does not resist the rearward movement of the deliverer acting under the tension of the spring 29. The spring 46, when under tension, is more powerful, obviously, 115 than the deliverer restoring spring 29 that connects with the arm 28.

As shown at D in Figs. 3 and 7, and also partially illustrated in other figures of the drawings, it is contemplated to employ a 120 valve *d* in the piston 7, together with certain mechanism to control the opening and closing of said valve. This valve is used preferably for governing to a certain extent the suction in the cylinder, acting as a 125 relief valve under certain conditions. The valve and its controlling mechanism will not be specifically described since any suitable means of this sort may be utilized with in the purview of the invention.

When five or more of the units herein described are arranged side by side, the operation of the deliverers of said units may be controlled by keys arranged alongside each unit, or keys which are grouped in a single keyboard common to all of the units. Furthermore, a group of units capable of delivering different denominations, such as just described, may be associated with coin or cash receptacles, and the delivery of money from the coin receptacles and bill-holders controlled from a common keyboard.

Having thus described the invention, what is claimed as new is:

15. 6. In a money paying machine, the combination of a bill holder, a deliverer associated therewith, suction means controlling relative movement of said parts whereby the deliverer may engage a bill on the holder, 70 said suction means acting also to cause the deliverer to hold the bill once engaged thereby, deliverer operating mechanism comprising an energy storing device, and means intermediate said holder and the energy storing device whereby to cause energy to be stored up in the latter, and means for utilizing the power of the energy storing device to actuate the deliverer.
16. 7. In a money paying machine, the combination of a bill holder and a relatively movable bill deliverer, operating means for effecting delivery movement of the latter, and pneumatic means for causing transfer of a bill from the holder to the deliverer, the 85 said deliverer operating means comprising an energy storing device adapted to be actuated by said pneumatic means.
17. 8. In a money paying machine, the combination of a bill holder and a deliverer movable relatively thereto, operating means for effecting delivery movement of the bill holder, automatic means for effecting a transfer of a bill from the bill holder to the deliverer, means intermediate said automatic 95 means and said operating means whereby on operation of the former energy is stored up in the latter, and means for locking and releasing said operating means.
18. 9. In a machine of the class described, the 100 combination of a money deliverer, means for causing successive delivery actions of said deliverer, a restraining device for the last named means, and manipulative means for releasing the deliverer and adapted for differentially controlling the latter in respect to the number of delivery actions of the same.
19. 10. In a machine of the class described, the combination of a money deliverer, means 110 normally tending to effect one or more delivery actions of said deliverer, a restraining device for the last named means, and means including a plurality of keys coöperative with the restraining device to release 115 the same and to cause one or more operations of the deliverer.
20. 11. In a machine of the class described, the combination of a money deliverer, means 120 normally tending to effect delivery action of said deliverer, a restraining device for the last named means, and keys coöperative with said restraining means to release the deliverer, and means coacting with the keys embodying an adjustable detent whereby 125 each key is operable to regulate a predetermined one or more operations of the deliverer.
21. 12. In a money paying machine, a vertically movable bill holder, a horizontally 130

movable deliverer, pneumatic means for effecting relative movement of said parts to transfer a bill from the holder to the deliverer, an operating device controlled from 5 said pneumatic means and adapted to actuate the deliverer, and means for locking and releasing said operating device.

13. In a money paying machine, the combination of a holder, a deliverer therefor, 10 means for causing relative movement of said parts to supply a piece of money to the deliverer from the holder, and means for actuating the deliverer comprising a normally inoperative member adapted to have 15 power stored up therein by the means for effecting relative movement aforesaid.

14. In a money paying machine, the combination of relatively movable bill holding and bill delivery devices, means for effecting 20 relative movement of said devices whereby to cause transfer of a bill from the holding to the delivery device, means for operating the delivery device to deliver the bill to a suitable point, means normally restraining 25 said operating means to prevent delivery of the bill by the delivery device, and mechanism intermediate said means for effecting relative movement of the first named parts and said operating means whereby the 30 latter is controlled in action by the former.

15. In a money paying machine, the combination of a movable deliverer, a bill holder, means for moving the bill holder relative to the deliverer to control its action 35 in supplying a bill to the latter, means for actuating the deliverer controlled by the last mentioned means, a device for restraining the deliverer actuating means, and means for releasing the restraining means 40 from said device.

16. In a money paying machine, the combination of a bill holder, a deliverer therefor, and means for imparting movement to the deliverer controlled by removal of a 45 bill from the deliverer.

17. In a money paying machine, the combination of a money holder, a deliverer therefor, means for imparting successive delivery movements to the deliverer controlled 50 by removal of a bill from the deliverer, and means to differentially control the last mentioned means.

18. In a money paying machine, the combination of a money holder, a deliverer therefor, 55 an energy storing device for causing successive delivery movements of the deliverer, means for restraining said deliverer from movement, and manipulative means coacting with the restraining means to control the cooperation of the said device with the deliverer.

19. In a money paying machine, the combination of a vertically movable bill holder, a relatively 60 movable bill deliverer, a piston connected with the holder, suction means

connected with said piston to withdraw the holder from the deliverer, spring means cooperative with the piston to force the holder toward the deliverer, operating means for the deliverer, means intermediate the operating means and said piston whereby to control the action of the operating means, and locking and releasing means for said operating means.

20. In a money paying machine, the combination of a movable bill holder, a movable deliverer associated therewith, means for automatically effecting relative movement of the holder and deliverer to supply a bill to the latter, means operable by the last mentioned means for imparting delivery movement to the deliverer, restraining means for the deliverer, and a differentially operable detent controlling said restraining means.

21. In a money paying machine, the combination of a movable bill holder, a movable deliverer associated therewith, means for automatically effecting relative movement of the holder and deliverer to supply a bill to the latter, means operable by the last mentioned means for imparting delivery movement to the deliverer, restraining means for the deliverer, and a manually operable detent controlling said restraining means and itself adapted for operation by delivery movement of the deliverer.

22. In a money paying machine, the combination of a bill holder, a deliverer therefor, means to move the holder toward the deliverer to supply a bill to the latter, suction means for withdrawing the holder from the deliverer and for causing the deliverer to positively engage and separate a bill from the holder, and means for operating the deliverer controlled by said suction means.

23. In a money paying machine, the combination of a bill holder, a deliverer therefor, means to move the holder toward the deliverer to supply a bill to the latter, suction means for withdrawing the holder from the deliverer and for causing the deliverer to positively engage and separate a bill from the holder, and mechanism for operating the deliverer comprising an operating member, and means operable by the suction means to store up power in the operating member.

24. In a money paying machine, the combination of a bill holder, a deliverer therefor, means to move the holder toward the deliverer to supply a bill to the latter, suction means for withdrawing the holder from the deliverer and for causing the deliverer to positively engage and separate a bill from the holder, mechanism for operating the deliverer comprising an operating member and means operable by the suction means to store up power in the operating member,

and means for restraining said operating member and for releasing the same.

25. In a money paying machine, the combination of a bill holder, a deliverer therefor, means to move the holder toward the deliverer to supply a bill to the latter, suction means for withdrawing the holder from the deliverer and for causing the deliverer to positively engage and separate a bill from the holder, mechanism for operating the deliverer comprising an operating member and means operable by the suction means to store up power in the operating member, means for restraining said operating member, a differentially movable detent coacting with the restraining means, and keys for operating said detent.

26. In a money paying machine, the combination of a bill holder, a deliverer, suction means for moving the holder and for causing the deliverer to engage and separate a bill from the pile on the holder, means for actuating the deliverer, and valve means controlling the action of the suction means 25 in respect to both the holder and deliverer.

27. In a money paying machine, the combination of a bill holder, a deliverer, suction means for moving the holder and for causing the deliverer to engage and separate a bill from the pile on the holder, means for actuating the deliverer, and valve means comprising separate valves controlling the action of the suction means in respect to the deliverer and holder.

35. 28. In a money paying machine, the combination of a money holder, a deliverer, means for causing relative movement of said parts to supply a piece of money to the deliverer, a support for the deliverer, and 40 a rotatable connection between said deliverer and support and comprising interlocking elements separable by longitudinal and rotary movement of the deliverer upon the support.

45. 29. A money paying machine comprising a money holder and deliverer, and automatic means controlled by the removal of money from the deliverer to cause one or more movements of the deliverer, each 50 movement effecting a separation of a piece of money from that carried by the holder and delivery of said money from the machine.

30. In a money paying machine, the combination of a deliverer, a money holder, pneumatic means for effecting relative movement of said parts, a lever for causing delivery movement of the deliverer, an operating bar for said lever, instrumentalities 55 intermediate the pneumatic means and said operating bar for setting the latter for operation, actuating means for the operating bar, and mechanism controlling the locking and releasing of said operating bar.

65. 31. In a money paying machine, the com-

bination of a deliverer, a money holder, pneumatic means for effecting relative movement of said parts, a lever for causing delivery movement of the deliverer, an operating bar for said lever, instrumentalities 70 intermediate the pneumatic means and said operating bar for setting the latter for operation, actuating means for the operating bar, mechanism controlling the locking and releasing of said operating bar and including a stop arm connected with said lever, means for locking said stop arm in a predetermined position, and a manipulative device for releasing the stop arm.

32. In a money paying machine, the combination of a deliverer, a money holder, pneumatic means for effecting relative movement of said parts, a lever for causing delivery movement of the deliverer, an operating bar for said lever, instrumentalities 85 intermediate the pneumatic means and said operating bar for setting the latter for operation, actuating means for the operating bar, mechanism controlling the locking and releasing of said operating bar and including a stop arm movable with said lever, a catch to hold said stop arm in a position preventing movement of the lever by the operating bar, and manipulative means to differentially actuate said catch.

95. 33. In a money paying machine, the combination of a deliverer, a money holder, pneumatic means for effecting relative movement of said parts, a lever for causing delivery movement of the deliverer, an operating bar for said lever, instrumentalities 100 intermediate the pneumatic means and said operating bar for setting the latter for operation, actuating means for the operating bar, mechanism controlling the locking and releasing of said operating bar and including a stop arm movable with said lever, a catch to hold said stop arm in a position preventing movement of the lever by the operating bar, and manipulative means to 105 differentially actuate said catch and consisting of a detent connected with the catch and operable by the stop arm.

34. In a money paying machine, the combination of a deliverer, a money holder for 110 supplying the deliverer, means for effecting relative movement of said parts including a piston, suction means adapted to act on said piston, a lever connected with the deliverer, an operating bar for said lever, a 120 spring for actuating the operating bar, means for moving the said piston in a direction opposite that in which it is moved by the suction means, an instrumentality intermediate the last mentioned means and the 125 actuating spring aforesaid to store up energy in said spring, and means for locking and releasing the deliverer.

35. In a money paying machine, the combination of a deliverer, means for supply- 130

- ing pieces of money to the deliverer, means for imparting successive movements to the deliverer, and mechanism controlling the number of successive movements including a stop arm connected with the deliverer, a catch for holding said arm in locked position, and means for moving said catch into different positions whereby one or more movements of the deliverer will be effected.
- 10 36. In a money paying machine, the combination of a deliverer, means for supplying pieces of money to the deliverer, means for imparting successive movements to the deliverer, and mechanism controlling the number of successive movements including a stop arm connected with the deliverer, a catch coöoperating with said arm to prevent movement of the deliverer, a differentially movable detent for holding said catch in adjusted positions disengaged in relation to the arm and itself operable for normalization by the arm, keys, and means intermediate the keys and the detent for imparting the variable movement aforesaid to the de-
